REMOTE RADIO TUNING CONTROL SYSTEM

Eugene F. McDonald, Jr., Winnetka, Ill.

Application December 10, 1942, Serial No. 468,478

14 Claims. (Cl. 250—20)

1

This invention relates to control systems, and more particularly to control systems for use by persons whose attention must be focused elsewhere. In Patent No. 2,216,671, for Radio control system, issued to me on October 1, 1940, I have disclosed and claimed a control system for a radio receiver mounted in a vehicle whereby the driver of the vehicle can silence the receiver and change the tuning adjustment of the receiver by a foot operation without diverting his attention from driving the vehicle. In my United States Letters Patent No. 2,307,329, issued to me January 5, 1943, for Radio control system, I have disclosed and claimed an improved control system of the same type in which such foot operation mechanically silences the radio receiver, and then, if desired, changes the tuning adjustment and in which the foot operation does not interfere with the manual operation when it is desired instead of foot operation. In my copending application Serial No. 390,406, filed April 25, 1941, now Patent No. 2,346,177 granted April 11, 1944, for Radio control system and multiple circuit switch, I have disclosed and claimed a further improvement in such a control system, in which foot operation is effective, in addition to producing the effects set forth above, to adjust the output volume of the radio receiver at the will of the driver without diverting his attention from operation of the vehicle.

An object of this invention is to provide a new and improved control system for use by a person whose attention must be focused elsewhere, which system includes means whereby the control system may be arranged at will either for operation by such person or for operation by some other person in a different position.

More specifically, it is an object of my invention to provide an improved control system for a radio receiver in a vehicle, the receiver having means whereby the driver can control the receiver by a foot operation without removing his attention from operation of the vehicle, or alternately control may be diverted for operation by other means.

The features of my invention which I believe to be novel are set forth with particularity in the appended claims. My invention itself, both as to its organization and manner of operation, together with further objects and advantages thereof, may best be understood by reference to the following description taken in connection with the accompanying drawings in which:

Figure 1 illustrates one embodiment of my invention;

2

Figures 2 to 8 illustrate various operating elements useful in the modification illustrated in Figure 1; and

Figures 9 and 10 illustrate other embodiments of my invention.

In Figure 1, a radio receiver arranged to be installed in a vehicle includes an antenna 10, a tuner, amplifier, and power supply represented by a rectangle 11, an electron discharge device 12 arranged to detect and amplify signals received by the antenna 10 and tuned and amplified by the tuner and amplifier 11, a power amplifier discharge device 13, and a speaker 14. The operation of the radio receiver is normal insofar as it successively receives a modulated carrier wave from the antenna 10, tunes and amplifies such wave through the tuner and amplifier 11, detects the signal in accordance with which the carrier wave is modulated, such detection being carried out in the circuits associated with the discharge device 12, amplifies such signal through devices 12 and 13, and reproduces the signal in speaker 14.

The signal detection circuit associated with the discharge device 12 includes a high frequency transformer 20 whose primary winding is energized by the amplified carrier wave from the tuner and amplifier 11, the secondary of transformer 20 being tuned to resonance at the frequency of such carrier wave by a condenser 21.

One terminal of the secondary of the transformer 20 is connected to the anode 22 of a diode section of the electron discharge device 12 and the other terminal is connected for high frequency currents through a condenser 23 to the cathode 24 of the device 12, which cathode is associated with the diode section including anode 22, and with a triode section including a control electrode 25 and an anode 26. To complete a path for continuous current through the anode 22, the cathode 24 is grounded, and that terminal of the secondary of the transformer 20 which is connected to the condenser 23 is grounded through two serially connected resistances 27 and 28.

A point between resistances 27 and 28 is connected to ground and to the cathode 24 through a high frequency by-passing condenser 30, whereby signals detected in the detection circuit appear across the resistance 28.

The signal across the resistance 28 is transferred through either of two circuits to be described hereinafter and through a coupling condenser 31 to the control electrode 25 of discharge device 12. This control electrode 25 is connected through a suitable grid resistance 32 to the

cathode 24. The anode 26 is connected through a suitable load resistance 33 to a source of positive potential illustrated schematically by the rectangle 11, which source of positive potential is supplied with power through a switch 34 from a suitable battery 35 which may be the storage battery of a vehicle.

Amplified signal potentials appearing across the load resistance 33 are amplified through the power amplifier discharge device 13, which is connected in usual fashion, and such amplified signals are transferred through an output transformer 36, the secondary of which is connected to energize the speaker 14.

One circuit for transferring signals from the resistance 28 to the control electrode 25 includes a volume control resistance 37, which is embodied in a unit 46, to be described hereinafter, suitable for mounting near the feet of an operator of a vehicle in which the receiver is mounted. The ungrounded terminal of the resistance 28 is connected through a switch 38, conductor 39, terminals 40 of a plug 41 and socket 42, and a conductor 43 to one terminal of resistance 37. The other terminal of resistance 37 is connected through a conductor 44 and terminals 45 of the plug 41 and socket 42 to ground. This ground is preferably the chassis of the receiver at a point near the points where cathode 24 and one terminal of resistance 28 are grounded. To ground a terminal of the resistance 37 in any other place would make it possible for extraneous voltage between such ground point and the chassis of the receiver to produce undesirable current flow through resistance 37, which would result in undesirable noise being produced in speaker 14.

The movable contact 50 of the volume control resistance 37 is connected through a conductor 51, terminals 52 of the plug 41 and socket 42, a switch 53, and the condenser 31 to the control electrode 25. By such connections, signal voltage appearing across the resistance 28 appears also across the volume control resistance 37, so that any desired portion of this signal voltage across resistance 37 may be impressed through movable contact 50 upon control electrode 25, thereby controlling the output of speaker 14. Suitable means are provided, as described hereinafter, to control the position of the movable contact 50 by a foot operation of the vehicle driver.

In the unit including the foot operated volume control resistance 37, there is also provided means operable by the foot of the vehicle driver for silencing the speaker 14 and for changing the tuning adjustment of the tuner represented by rectangle 11. This means includes a switch contact 54, movable by the foot of the vehicle driver, a second switch contact 55, movable when engaged with contact 54, and a third, fixed, switch contact 56. The contact 54 is connected through a conductor 57 and terminals 58 of the plug 41 and socket 42 to ground. The contact 56 is connected to switch 34 through a conductor 59, terminals 60 of the plug 41 and socket 42, a conductor 61, and the operating coil 62 of an electromagnet suitably arranged for changing the tuning adjustment of tuner 11. The contact 55 is connected through a conductor 63 and terminals 64 of the plug 41 and socket 42, to one terminal of the secondary of output transformer 36. The other terminal of the secondary of transformer 36 is grounded.

In operation the driver of a vehicle in which this receiver is installed may at will control the

output volume of the receiver by moving by a foot operation the movable contact 50 of the resistance 37, or he may depress the movable switch contact 54 until it touches contact 55, at which time a short circuit is placed across the secondary of output transformer 36, thereby instantaneously silencing the speaker 14. Such silencing is frequently desirable to allow conversation or to listen for train whistles at railroad crossings.

Further depression of the switch contact 54, so that it carries the movable contact 55 with it to complete a circuit between the contacts 54 and 56, energizes the operating coil 62 from battery 35, so long as switch 34 is closed, to change the tuning adjustment of the tuner represented by the rectangle 11 so as to receive a different station.

Switches 34, 38 and 53, as well as the movable contact 70 of a volume control resistance 71 are mechanically arranged to be controlled by operation of a single operating element, preferably so positioned that it may be operated by an occupant of a vehicle other than the driver, and preferably so located that it also may be operated by the driver.

Upon initial movement of this operating element, to be more fully described hereinafter, from one extreme position, the switch 34 is first closed without affecting switches 38 and 53 so as to energize the receiver power supply represented by the rectangle 11, and so as to connect the operating coil 62 of the station selecting electromagnet in readiness for energization by the movable contact 54 in unit 46. A slight additional movement of this operating element is effective then to change the positions of switches 38 and 53, so as to disconnect the upper terminal of resistance 37 in unit 46 from resistance 28, and to disconnect the movable contact 50 from condenser 31. The movement of switch 38 simultaneously connects volume control resistance 71 in parallel with resistance 28, and the movement of switch 53 simultaneously connects the movable contact 70 of volume control resistance 71 through condenser 31 to the control electrode 25. Still further movement of this operating element leaves switches 34, 38 and 53 in the positions, to which they have been moved, and thereafter moves contact 70 along resistance 71 to increase that portion of the signal potential across resistance 28 which is applied through resistance 71 to control electrode 25.

In Figure 2 there is shown a side view of such an operating element 80, illustrated as a knob which may suitably be turned by hand. This knob 80 is arranged to turn a shaft 81 on which is mounted the volume control resistance 71 and switches 34, 38 and 53. This unit may conveniently be so mounted that knob 80 is on the dash panel of the vehicle in which the receiver is mounted, so that it may conveniently be operated by the driver of the vehicle or by a passenger.

In Figure 3 there is shown an end view of this assembly in which an arrow 82 on the face of the knob 80 may be seen. When the knob 80 is turned in a clockwise direction, as indicated by the arrow 82, its initial movement mentioned heretofore, which is effective only to close the switch 34, covers an angle 83. Subsequent movement of the knob 80 through an additional angle 84 is effective as described hereinbefore to actuate the two switches 38 and 53, so as to change circuit connections of resistance 28 and condenser

series 31 from the volume control resistance 37 in unit 46 to the volume control resistance 71. Additional rotation of knob 80 thereafter through the angle 85 is effective to change the setting of the variable contact 10 on the volume control resistance 71, so as to apply any desired portion of the signal potential across resistance 28 between the control electrode 25 and cathode 24.

The volume control resistance 71 may be of a usual type in which rotation through a small angle at one end of the total angle through which it may be operated is effective to change the resistance to a very slight degree, if at all. Angles 83 and 84 should be at such end of the total angle of movement of knob 80. All, or by far the major part, of the resistance change in resistance 71 occurs during rotation of the knob 80 through the angle 85.

The switches 34, 38 and 53 may conveniently be of the type termed in the art "switch covers," which are so arranged that they may be fitted on the back of volume control resistance 71, of usual form, and are actuated during rotation of the shaft 81 of the volume control resistance through a desired part of its angular movement.

In Figure 4, there is illustrated one modification of the unit 46 shown schematically in Figure 1. This modification of unit 46 is fully described and claimed in my co-pending application Serial No. 406,677, filed August 13, 1941, now Patent No. 2,374,873, granted February 21, 1945, for Radio control system and multiple circuit switch. Briefly, the casing 90 of this unit is so arranged that it may be conveniently placed on the floor board of a vehicle such as an automobile, and a foot button 91 on the top of casing 90 is arranged so that it may be either depressed or rotated with respect to the casing 90. Rotation of the button 91 by the foot of the vehicle operator is effective to rotate the shaft 92 of the volume control resistance 37, which is schematically shown in unit 46 of Figure 1. Depression of the button 91 by the foot of the vehicle operator is effective first to compress a relatively weak spring 93 and complete a connection between the grounded contact 54 of the foot button 91 and the movable contact 55, both of which are illustrated schematically in Figure 1. Further depression of the foot button 91 is effective to compress the relatively stronger spring 94 and, while maintaining a connection between the grounded movable contact 54 and movable contact 55, moves both of these contacts down, so that connection is made between the movable contact 55 and the fixed contact 56, which are all schematically illustrated in Figure 1.

In Figure 5 only the central supporting plate 95 of the switch body 90 is illustrated together with the fixed contact 56 and the movable contact 55 and associated wiring. The conductor 57, shown in Figure 1 as being connected between movable switch contact 54 and ground through the plug 41 and socket 42, is shown in Figure 5 to be a shielding braid like that around the two conductors 43 and 51, which, as shown in Figure 1, are passed through the shielding braid which constitutes the conductor 44 of Figure 1. It is desirable that the two sets of conductors be thus shielded, not only from each other, but from external electrostatic and electromagnetic fields, so as to reduce the possibility of introducing undesirable voltages into conductors attached to the volume control resistance 37. Introduction of such undesirable voltage into resistance 37 results in the production of noise in the speaker

14 which interferes with proper reproduction of signals.

In Figure 6 there is illustrated an alternative form of foot switch for performing the same function as the unit illustrated in Figures 4 and 5. Briefly, this unit comprises a housing 100 adapted to be placed on the footboard of a vehicle near the operator. A wheel 101 is mounted within the housing 100 upon the shaft of a volume control resistance unit 102, which is in turn supported through a spring 103 from the housing 100. A portion of the wheel 101 projects through an opening 104 in the housing 100, so that the vehicle operator may depress the wheel 101 within the housing 100 by his foot, or alternatively may turn the wheel 101 by his foot. Turning of the wheel 101 is effective to adjust the volume control resistance 102 and depression of the wheel 101 within the housing 100 is effective to bend downwardly the free end 105 of the spring 103 on which two movable contacts 106 and 107 are carried. Two cooperating fixed contacts 108 and 109 are mounted upon insulation fixed to a part of the housing 100 and are so arranged that as the end 105 of the spring 103 moves downwardly, the movable contact 106 first touches the contact 108 and later movable contact 107 touches fixed contact 109.

Circuit connections are made through these fixed and movable contacts in a manner like that described for the unit 46 illustrated in Figures 4 and 5. Conductor 51 is connected to the housing 100 and through the spring 103 to the movable contacts 106 and 107. Conductor 63 is connected to the fixed contact 108, and conductor 59 to the fixed contact 109. Upon depression of the wheel 101 within the housing 100, a circuit is first completed between conductors 57 and 63, as is the case with unit 46 illustrated in Figure 1, and a second circuit is thereafter completed between conductors 51 and 59, thereby first producing silencing of the speaker 14, and thereafter producing a station changing operation, by means of the operating coil 62 of the station selecting electromagnet.

The vehicle operator, upon depressing the wheel 101 within the housing 100, senses by pressure the point at which contacts 106 and 108 touch, and can, if so desired, stop depression of the wheel 101 at that point. The increased pressure required to depress wheel 101 further is quite sensible since further depression of the wheel 101 must not only cause the bending of spring 103 at its upper portion, but also must cause bending of the lower end of spring 105 adjacent contacts 106 and 107, so as to allow contact 107 to touch contact 109. By this construction therefore, the same results are attained as with the unit 46 illustrated in Figure 4, in which the relatively weak spring 93 is first compressed and thereafter the relatively stronger spring 94 is compressed to complete the final station changing connection.

In Figure 7, there is shown an alternative arrangement of volume control resistance 71 and knob 80 with switch elements which differ to some extent from those illustrated in Figures 2 and 3. A single switch cover 34 is attached to the back of the volume control resistance 71, as is quite common in radio receivers. A double pole, double throw, toggle switch 110 is arranged so as to be operated by rotation of the shaft 81 so as to perform the functions performed in the embodiment of Figure 2 by switches 38 and 53.

To this end the toggle switch 110 is mounted with its operating handle 111 facing toward the shaft 81 and arranged for movement in a plane perpendicular to that shaft. A resilient operating member 112 is attached to the shaft 81 and is sufficiently long to engage the operating handle 111 during a certain portion of the angular rotation of knob 80.

The resilient member 112 is affixed to the shaft 81 at a certain angle, as may be seen in Figure 8, and is just long enough and possesses just sufficient resilience that, during rotation of the knob 80, the member 112 engages the operating handle 111 and moves it to its opposite position, and thereafter bends sufficiently so that the end of member 112 passes over the end of handle 111. Opposite rotation of the knob 80 thereafter causes member 112 to engage the opposite side of handle 111 and thereupon move handle 111 to its initial position, then bending sufficiently to pass by handle 111.

The resilient member 112 is affixed to the shaft 81 at such an angle with respect to the angular position of knob 80 at the time when switch 34 operates, that switch 110 is operated immediately thereafter. That is, when knob 80 is in one extreme position, member 112 is spaced from the handle 111 by such a distance that, upon initial rotation of knob 80, switch 34 is operated by the time the resilient member 112 touches handle 111. Further rotation of the knob 80 operates switch 110 through the resilient member 112 and handle 111 as described, and thereafter further rotation of the knob 80 causes adjustment of the volume control resistance 71.

In Figure 9 many elements are identical with those illustrated in Figure 1, and are given like reference characters. In the modification illustrated in Figure 9, switch 38 is omitted, conductor 39 being connected directly to a point between resistances 27 and 28 and also to the ungrounded terminal of volume control resistance 71. By this connection the volume control resistances 37 and 71 are always connected in parallel when the plug 41 is in the socket 42, and operation of the switch 53 is effective to take signal voltage from either of these volume control resistances 37 and 71 and apply it to the control electrode 25 through the coupling condenser 31.

In order that selection may be made of the volume control which it is desired to use, switch 53 is arranged to be controlled in unison with the movable contact 70 of resistance 71 in a manner similar to that described in connection with Figure 7 for the volume control resistance 71 and switch 34. That is, in one extreme position of the control member which operates both switch 53 and movable contact 70, the parts are as illustrated in Figure 9. Initial movement of the operating member from this extreme position first operates the switch 53 to disconnect volume control resistance 37 from condenser 31 and to connect volume control resistance 71 thereto. Further movement of the operating member for switch 53 and movable contact 70 is effective to move the contact 70 along the volume control resistance 71, thereby to increase the volume of sound reproduced by speaker 14.

In order to connect or disconnect the source 35 of operating voltage with the power supply illustrated by rectangle 11, the switch 34 is provided with a separate operating member, and may conveniently be arranged to operate in unison with a tone control resistance 120. The movable contact 121 of the resistance 120 is connected

mechanically with the switch 34 so that initial movement of the operating member is effective to close switch 34 and subsequent movement of the operating member is effective to adjust the movable contact 121 along the tone control resistance 120.

In order that adjustment of the resistance 120 be effective to produce tone control, resistance 120 is connected in series with a condenser 122 between ground and conductor 39. Consequently, when the value of resistance 120 is low, a considerable proportion of high frequency components of the signal across resistance 28 is short circuited to ground through condenser 122, which is suitably made with a low reactance. When resistance 120 is adjusted to have a high value, substantially no signal current is diverted from conductor 39 to ground, the maximum value of resistance 120 being sufficiently high to prevent such diversion.

It may be noted that the terminal of resistance 28, which was illustrated in Figure 1 as being grounded, is illustrated in Figure 9 as being connected to ground through a by-passing condenser 130. In this circuit arrangement a path for continuous current from the anode 22 exists through the secondary of transformer 20, resistance 27, and through volume control resistances 71 and 37 in parallel back to the cathode 24 of the device 12.

A continuous voltage is developed across the condenser 130, which voltage is proportional to the average intensity of the carrier wave at transformer 20, and which voltage is suitable for automatic volume control purposes. To this end this voltage is applied at suitable points in the tuner and amplifier represented by rectangle 11 through conductor 131.

In Figure 10 many elements are identical with those illustrated in Figures 1 and 9, and are given like reference characters. In this arrangement the volume control resistance 71 is omitted entirely, and a resistance 140 having two taps 141 and 142 is connected between ground and a point between resistances 27 and 28. A multiple push-button switch 143 is arranged in some position where it may be conveniently operated either by the vehicle driver or by another occupant of the vehicle. This switch 143 is so arranged that its five buttons respectively function: (O) to disconnect all operating power from the receiver; (F) to transfer control of speaker volume to unit 46; (1) to operate the receiver with loud output volume independently of unit 46 except for its muting and station changing control; (2) to operate the receiver as in case (1) with medium output volume; and (3) to operate the receiver as in case (1) with low output volume.

To this end the switch 143 includes five buttons marked respectively "O," "F," "1," "2" and "3," which buttons respectively correspond to the above enumerated operations. These buttons have respective contact bridges 144, 145, 146, 147 and 148. The buttons of the switch 143 are arranged with shoulders, such as the shoulder 150 of the button marked "3," to cooperate with a laterally slideable latch bar 151, so that depression of any button automatically releases all other buttons and locks the depressed button in the downward position. The button marked "2" is illustrated in the position in which the latch bar 151 holds it down. A spring 152 tends to move the latch bar 151 to the right, thereby locking down any button when its shoulder 150 is beneath the latch bar 151, and releasing that but-

ton whenever another button is depressed so that the shoulder of the button being depressed moves the latch bar 151 to the left.

The button marked "O" is effective to de-energize the entire receiver by reason of the fact that the power supply indicated by the rectangle 11 is supplied through conductor 153 with current from the source 35 of potential only when the button marked "O" is in its upward position, so that the contact bridge 144 maintains connection between contact 154 connected to conductor 153 and contact 155 connected to the positive terminal of source 35, the negative terminal of source 35 being grounded. Whenever the button marked "O" is depressed, the contact bridge 144 moves away from contacts 154 and 155, and disconnects the source 35 of potential from the receiver.

The contact bridge 145 of the button marked "F" of switch 143 cooperates with contacts 160, 161, 162 and 163 so that when the button marked "F" is in its upward position, connection is made between the contacts 160 and 162, and when the button marked "F" is in its downward position connection is made between the contacts 161 and 163. Contact 160 is grounded, preferably at the chassis of the receiver. Contact 161 is connected to a point between resistances 21, 28 and 140. Contact 162 is connected to the cathode 24 of the discharge device 12 and also to terminals 164 of plug 165 and socket 166, which are connected to the movable contact 50 of the volume control resistance 37 in unit 46. Contact 163 of switch 143 is connected through condenser 31 to the control electrode 25 of device 12.

When the button marked "F" of switch 143 is in its upward position, the cathode 24 of the discharge device 12 is grounded through a circuit which may be traced from the cathode 24, contact 162, contact bridge 145, and contact 160 to ground. No connection is made between contact 161 and 163 so that no signal voltage from resistance 140 is applied through circuits connected with the button marked "F" to the control electrode 25 of device 12.

When the button marked "F" of switch 143 is in its downward position, the cathode 24 of device 12 is connected to ground only through the movable contact 50 of volume control resistance 37 in unit 46 to which it is connected through the terminals 164 of plug 165 and socket 166. In that position of the button marked "F," the contact bridge 145 completes a connection between contacts 161 and 163, so that the control electrode 25 of the discharge 12 is connected through condenser 31 to a point between resistances 21 and 28, whereby the entire signal potential across resistance 140 is impressed between control electrode 25 and ground. When the button "F" is thus connected, circuits are completed with the volume control resistance 37 of unit 46 so that signal potentials from the secondary of transformer 36 are impressed in degenerative phase between cathode 24 and ground, whereby adjustment of the adjustable contact 50 of volume control resistance 37 is effective to adjust the amount of such degenerative feedback, and thereby adjust the overall amplification of signal potential across the resistance 140 through devices 12 and 13 so that they are reproduced by the speaker 14 in volume determined by the setting of adjustable contacts 50 of resistance 37.

To this end the conductor 57, which is the shield braid of a three conductor cable including conductors 59 and 63 and the conductor between

the terminals 164 and the contact 50 of resistance 37, is connected through the terminals 170 of plug 165 and socket 166 to ground. Conductor 63, which is connected to the movable contact 55 of unit 46 is also connected to one terminal of resistance 37, conductor 57 being connected to the other terminal. Conductor 63 extends from movable contact 55 of unit 46 to the plug 165 and is connected to terminals 171 of the plug 165 and socket 166 and to conductor 172, which in turn is connected to one terminal of the secondary of output transformer 36, the other terminal of that secondary being grounded.

In order that unit 46 may cause station changing operation, the conductor 59 is connected between the stationary contact 56 and coil 62 through terminals 173 of plug 165 and socket 166. The movable contacts 54 and 55 of the unit 46 are thus connected each to one terminal of the secondary of transformer 36, and the muting and station changing operations of unit 46 are identical with those described in connection with Figure 1.

In order that the degenerative feedback from the output of the amplifier including discharge devices 12 and 13 to the input thereof may be better understood, the circuits involving this degenerative feedback are described, when the button marked "F" of switch 143 is in its downward position. The input circuit of the device 12 for currents of signal frequency extends from the control electrode 25 through condenser 31, contact 163, contact bridge 145, contact 161, resistance 140, ground, terminals 170 of socket 166 and plug 165, conductor 57, that portion of resistance 37 between conductor 57 and movable contact 50, contact 50, terminals 164 of plug 165 and socket 166, and thus to the cathode 24 of the device 12. Amplified signal potentials from the anode 26 appear across the secondary of output transformer 36, which is included in a circuit as follows: One terminal of the secondary of output transformer 36 is connected through conductor 172, terminals 171 of socket 166 and plug 165, conductor 63, resistance 37, conductor 57, terminals 170 of plug 165 and socket 166, and ground back to the other terminal of the secondary of output transformer 36.

It is notable that both of these circuits include that portion of the resistance 37 between the movable contact 50 and the conductor 57. Current flowing through such portion of the resistance 37, which current is proportional to the amplified signal potential energizing speaker 14, produces a voltage across such portion of resistance 37, which voltage is in the input circuit of the discharge device 12, and is in phase opposition to the signal potential developed across the resistance 140 to be amplified through device 12.

Adjustment of the adjustable contact 50 along resistance 37 is therefore effective to reduce the amount of degenerative feed back as contact 50 is moved toward that end of resistance 37 connected to conductor 57, whereby the overall amplification of discharge devices 12 and 13 is increased so as to increase the sound output of speaker 14. Conversely, as the movable contact 50 is adjusted downward so as to be nearer conductor 63, the degenerative feed back from output transformer 36 to the input of discharge device 12 is increased, whereby the overall degenerative feedback is increased and the net gain through discharge devices 12 and 13 is re-

duced thereby reducing the sound output of the speaker 14.

Discharge current flowing between the anode 26 and cathode 24 of device 12 flows also through the resistance 37, and produces a continuous potential thereacross, which appears between the diode anode 22 and cathode 24 with such polarity as to make diode anode 22 negative with respect to cathode 24. It is usually undesirable that such a bias potential should exist between the anode and cathode of a diode detector arrangement, but so long as the continuous potential developed across resistance 37 be not more than about one volt, such bias potential is tolerable. It is notable that, when the button marked "F" is in its upward position, the cathode 24 is grounded so that no continuous potential exists across the resistance 37 and no bias potential exists between the diode anode 22 and cathode 24 of device 12.

When the button marked "1" of switch 143 is in its downward position, the contact bridge 146 completes a connection between contacts 180 and 181. Contact 180 is connected to contact 181 and to a point between resistances 27, 28, and 140, and contact 181 is connected to contact 163, and to contact 183 and 185, associated respectively with buttons marked "2" and "3" of switch 143. Depression of the button marked "1" therefore completes a circuit between control electrode 25 through condenser 31 to the ungrounded terminal of resistance 140, whereby the entire signal potential across resistance 140 is impressed between the control electrode 25 and cathode 24, so that the sound output of the speaker 14 is maximum.

When button "2" of switch 143 is depressed, the contact bridge 147 completes the connection between the contacts 182 and 183, and since contact 182 is connected to the tap 141 of resistance 140, only that portion of the signal potential across resistance 140 which exists between tap 141 and ground is applied between the control electrode 25 and cathode 24 of the discharge device 12. Accordingly, the sound output of the speaker 14 is reduced in proportion as the resistance between tap 141 and ground is less than the total amount of resistance 140.

Depression of the button "3" of switch 143 completes a connection between contacts 184 and 185, and since contact 184 is connected to tap 142 of resistance 140, the still smaller signal potential between tap 142 and ground across resistance 140 is the only part of the entire signal potential across resistance 140 which is applied between control electrode 25 and cathode 24 of device 12. Accordingly, the sound output of speaker 14 is still further reduced.

Control of the sound output of speaker 14 from the foot control unit 46 of Figure 10 by means of degenerative feedback, as illustrated, has an important advantage in that signal potentials necessarily present in the unit 46 between the movable contacts 54 and 55 for muting purposes, need not be carefully shielded from volume control resistance 37, as would be necessary if the only potentials across the resistance 37 were the small signal potentials developed by the signal detection produced in the detecting circuit including diode anode 22 and anode 24. Furthermore, extraneous currents induced in the various conductors involved in the degenerative feedback circuits have little effect upon the output of speaker 14 because of low impedance characteristics of such degenerative feedback circuits.

While I have shown and described the particular embodiments of my invention, it will be obvious to those skilled in the art that changes and modifications may be made without departing from my invention in its broader aspects, and I, therefore, aim in the appended claims to cover all such changes and modifications as fall within the true spirit and scope of my invention.

I claim:

10. A control system for controlling a radio receiver for an automobile, comprising means operable by the foot of the automobile driver for controlling the volume of output of said radio receiver, means operable on the dash panel of said automobile for controlling the volume of output of said radio receiver, and means responsive to an adjustment of said means on said dash panel for transferring control between said means on said dash panel and said foot operable means.
15. In a system for controlling the output volume of a radio receiver in a moving vehicle, said receiver having a first portion including a signal detector, and a second portion including a signal amplifier and reproducer, means for controlling the output volume of said radio receiver by adjusting the amount of signal transferred from said detector to said amplifier, said means being operable by the operator of said vehicle whose attention must be focused upon the operation of said vehicle, means placed at a position different from said first means for adjusting the amount of signal transferred from said detector to said amplifier, and means responsive to an adjustment of said last means for transferred control over 35 said output volume from said first means to said last means.
20. In a control system for controlling the output volume and tuning of a radio receiver in a moving vehicle, means for controlling such output volume operable by the operator of said vehicle whose attention must be focused upon the operation of said vehicle, said means being also arranged upon operation by said operator to reduce the output volume of said receiver substantially to zero instantaneously and thereafter at the will of said operator to adjust the tuning of said receiver, means for controlling said output volume located at a position different from said first means, and means responsive to an adjustment of said last means for transferring control over said output volume from said first means to said last means.
25. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
30. In a system for controlling the output volume of a radio receiver on a moving vehicle, means for controlling said output volume operable by the operator of said vehicle whose attention must be focused upon the operation of said vehicle, differently positioned means manually accessible by said operator for controlling said output volume and for transferring control of
35. In a system for controlling the output volume of a radio receiver on a moving vehicle, means for controlling said output volume operable by the operator of said vehicle whose attention must be focused upon the operation of said vehicle, differently positioned means manually accessible by said operator for controlling said output volume and for transferring control of
40. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
45. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
50. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
55. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
60. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
65. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
70. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.
75. In a system for controlling the output volume of a radio receiver on a moving vehicle, means for controlling such output volume operable by the operator of said vehicle whose attention must be focused upon the operation of said vehicle, means positioned differently from said first means for controlling said output volume, means for controlling the supply of power to said receiver, and means for controlling said differently positioned volume control means, said power control means, and the transfer of control between said first volume control means and said differently positioned volume control means by a manual operation performable by said operator.

13

said output volume between said two means, and separate manually operable means for controlling the supply of power to said receiver and the output tone of said receiver.

6. In a system for controlling the output volume of a radio receiver having a first portion including a signal detector and a second portion including a signal amplifier and reproducer, means for controlling said output volume at one position effective to adjust the amount of signal transferred from said signal detector to said amplifier, means for feeding signal from the output of said amplifier to the input thereof in degenerative sense and in adjustable amounts to adjust said output volume, said signal feeding means being located at a position different from said one position, and means for transferring independent control between said first two means.

7. In a system for controlling the output volume of a radio receiver including a first portion having a signal detector and a second portion having a signal amplifier and reproducer, means at one position for feeding signal from the output of said amplifier to the input thereof in degenerative sense, and in adjustable amounts to adjust said output volume, and means for adjusting the output volume of said receiver at another position by disabling said first means and adjusting the amount of signal transferred from said signal detector to said amplifier.

8. In a system for controlling the output volume of a radio receiver in a moving vehicle, said receiver having a first portion including a signal detector and a second portion including a signal amplifier and reproducer, means for controlling such output volume operable by the operator of said vehicle whose attention must be focused upon the operation of said vehicle, said means being arranged to feed signals in degenerative sense and in adjustable amount from the output to the input of said amplifier, means in a different position from said first means for controlling said output volume, and means responsive to an adjustment of said last means for transferring control over said output volume between said first means and said last means.

9. A control system for controlling a radio receiver in a vehicle, comprising means operable by the foot of the vehicle driver for adjusting the volume of output of said receiver, means located elsewhere at a point remote from the first-mentioned means in said vehicle for adjusting the volume of output of said receiver, and means actuated simultaneously in response to actuation of said means located elsewhere for transferring permanently control over adjustment of said output volume between said foot operable adjusting means and said second adjusting means.

10. A control system for controlling a radio receiver in a vehicle, comprising means operable by the foot of the vehicle driver for adjusting the volume of output of said receiver, means located elsewhere at a point remote from the first-mentioned means in said vehicle for adjusting the volume of output of said receiver, and means responsive to an adjustment of one of said adjusting means for transferring permanent control over adjustment of said output volume between said two adjusting means.

11. A control system for controlling a radio receiver in a vehicle, comprising a first means operable by the foot of the vehicle driver for adjusting the volume of output of said receiver, and second means located at a position in said ve-

14

hicle remote from said first means for consecutively disabling permanently said foot operable adjusting means to control adjustment of said output volume and thereafter adjusting the volume of output of said receiver.

12. In a control system for a radio receiver in a vehicle, said receiver having means for sequentially selecting predetermined signals and means for muting the output volume of said receiver, the combination of a footswitch located for convenient operation by the vehicle driver while his attention is absorbed in the operation of said vehicle, said footswitch having a member operable in one fashion to cause said muting means to mute the output volume of said receiver and operable further in the same fashion to cause said signal selecting means to select a predetermined signal, said member of said footswitch being operable in a different fashion for adjusting over a range the output volume of said receiver, means located in said vehicle at a position remote from said footswitch for adjusting over a range the output volume of said receiver, and means for transferring control of the adjustment of said output volume from said footswitch to said means at a different position.

13. In a control system for a radio receiver in a vehicle, said receiver having means for sequentially selecting predetermined signals and means for muting the output volume of said receiver, the combination of a footswitch located for convenient operation by the vehicle driver while his attention is absorbed in the operation of said vehicle, said footswitch having a member operable in one fashion to cause said muting means to mute the output volume of said receiver and operable further in the same fashion to cause said signal selecting means to select a predetermined signal, said member of said footswitch being operable in a different fashion for adjusting over a range the output volume of said receiver, and means located at a position in said vehicle remote from said footswitch for consecutively disabling said footswitch to control adjustment of said output volume and thereafter adjusting the volume of output of said receiver.

14. In a control system for a radio receiver in a vehicle, said receiver having means for sequentially selecting predetermined signals and means for muting the output volume of said receiver, the combination of a footswitch located for convenient operation by the vehicle driver while his attention is absorbed in the operation of said vehicle, said footswitch having a member operable in one fashion to cause said muting means to mute the output volume of said receiver and operable further in the same fashion to cause said signal selecting means to select a predetermined signal, said member of said footswitch being operable in a different fashion for adjusting over a range the output volume of said receiver, means located at a position in said vehicle remote from said footswitch for consecutively disabling said footswitch to control adjustment of said output volume and thereafter adjusting the volume of output of said receiver, and means for resisting movement of said member and said footswitch to cause the muting means to mute the output volume of said receiver and for resisting with sensibly greater resistance further movement of said member in the same fashion to cause said signal selecting means to select a desired signal.

Certificate of Correction

Patent No. 2,445,031.

July 13, 1948.

EUGENE F. McDONALD, JR.

It is hereby certified that error appears in the printed specification of the above numbered patent requiring correction as follows: Column 12, line 34, for the word "transferred" read *transferring*; and that the said Letters Patent should be read with this correction therein that the same may conform to the record of the case in the Patent Office.

Signed and sealed this 12th day of October, A. D. 1948.

[SEAL]

THOMAS F. MURPHY,
Assistant Commissioner of Patents.
